UNITED STATES PATENT OFFICE.

ROBERT E. PETEET, OF ABERDEEN, MISSISSIPPI.

TOY.

No. 921,450.

Specification of Letters Patent.

Patented May 11, 1909.

Application filed November 17, 1908. Serial No. 463,026.

To all whom it may concern:

Be it known that I, ROBERT E. PETEET, a citizen of the United States, residing at Aberdeen, in the county of Monroe and State of 5 Mississippi, have invented new and useful Improvements in Toys, of which the following is a specification.

This invention relates to toys and one of the principal objects of the same is to provide simple and efficient mechanism for operating articulated toy figures.

Another object of the invention is to provide means for operating a vibratory spring board for causing an articulated figure to 15 dance, said mechanism being provided with a start and stop lever.

Still another object is to provide a toy of an amusing and entertaining character which may be wound up to be operated for a comparatively long time and which can be thrown into and out of operation by the movement 20 of a lever.

These and other objects may be attained by means of the construction illustrated in 25 the accompanying drawings, in which:—

Figure 1 is a side elevation of a toy made in accordance with my invention. Fig. 2 is a front end elevation of the operative mechanism suspended from a table or platform. 30 Fig. 3 is a transverse sectional view of the same from the rear of the toy. Fig. 4 is a plan view of the table or platform and the spring board mounted thereon. Fig. 5 is a detail vertical sectional view illustrating 35 the manner of mounting the spring board, the umbrella shaft and the lantern.

Referring to the drawings, the numeral 1 designates a table or platform supported upon twisted wire legs 2 secured by means 40 of screws 3 underneath said table. The wire legs 2 may be independently bent in order to secure a firm support for the table on an uneven surface. The table 1 has its central portion cut away as at 4 and mounted in the cut 45 away portion is a spring board 5, said board being substantially of the same contour as the opening 4 and connected to the table 1 by means of the spring 6 secured at one of its ends 7 under the table 1 and at its other end 50 by means of the fastenings 8 connected to the spring board 5.

Suspended under the table is a frame 9 in which is mounted a train of clock work gearing comprising a wheel 10 and a spring 11 on 55 the shaft of said wheel. On the outer end of said shaft a winding key 12 is secured.

The wheel 10 is in mesh with a pinion upon a shaft 13 to which is secured a gear wheel 14, said wheel 14 meshing with a pinion 15 on the shaft 16. The wheel 14 also meshes with 60 a pinion on the shaft 17 which shaft carries the wheel 18. The shaft 16 extends backwardly under the table 1 and is provided with a tappet 19 which strikes a spring 21 at each revolution, said spring being connected 65 to the spring board at 22. The wheel 10 is mounted on the shaft 10^a, and said shaft extends backwardly under the table 1 and is supported by the hanger 23.

Mounted on the shaft 10^a is a gear wheel 70 24 which meshes with a similar gear 25 mounted upon the lower end of a vertical shaft 26, said shaft carrying an umbrella 27 at its upper end. The umbrella shaft 26 extends through a tube 28 mounted upon a 75 supporting block 29, and resting upon the upper end of the tube 28 is a lantern 30 having cut out figures 31 and designed to hold a candle 32. The top 33 of the lantern is spaced from the upper edges of the lantern 80 30 by means of spring fingers 34. An articulated figure 35 is supported upon a spring wire standard 36 connected to the figure at one end and attached to the cylinder 28 at the opposite end. The figure 35 is 85 provided with pivoted arms 37 and legs comprising the thigh members 38 pivotally connected at 39 to the body and the lower leg sections 40 pivoted at 41 to the thigh sections 38. The feet 42 are located immediately above the spring board 5 so that as the spring board is vibrated the articulated members of the figure will move to 90 simulate dancing.

A lever 43 pivoted in the frame 9 is provided with an arm 44 adapted to engage the pinion 45 on the governor shaft 46, said shaft carrying the fan blades 47. The handle portion of the lever 43 extends from the top of the table 1 and is provided with a rack 48 95 for holding the lever in adjusted position. A flag staff 49 to which is connected a flag 50 is mounted upon the table 1 by means of a keeper 51, said flag staff having a horizontal portion 52 and a vertical member 53 extending through the table 1, said member 53 having a loop 54 thereon, said loop engaging the shaft 10^a and said shaft being mounted in a slot 55 in the frame 9. Thus when the flag staff 49 is moved to one side or the other, 100 the shaft 10 is moved to throw the mechanism into or out of gear. 105 110

A short shaft 56 mounted in a keeper 57 on the table 1 and passing through a block 58 secured to the table 1 is provided with a cranked end 59 disposed over the spring board 5 in such position as to be hit by the spring board at each movement to move the opposite angular end 60. Any suitable figure or toy may be operated by this arm.

The operative mechanism may be 10 closed within a suitable housing 61 as shown in Fig. 1 and if desired a railing 62 may be applied to the top of the table to conceal the lower portion of the figure 35. It will of course be understood that the figure 35 may be suitably dressed to represent any desired character.

The operation of my invention may be briefly described as follows. With the key 12 the spring 11 is wound and the machine 20 is started by moving the lever 43 into one of the notches of the rack 48. The speed may be regulated by moving the lever toward the right or left. As the shaft 10^a is rotated, rotation is imparted to the shaft 16 which 25 carries the tappet 19. The tappet 19 striking the spring 21 vibrates the spring board 5 on its spring 6. The umbrella 27 is rotated by means of the wheels 24 and 25 and the umbrella shaft 26 carries with it the lantern 30 30. The figure 35 is made to dance upon the spring board. The flag staff 49 may be moved to start and stop the mechanism.

From the foregoing it will be obvious that 35 my invention is of comparatively simple construction, is amusing and entertaining to old and young, can be wound up to run a considerable time, and that various figures may be connected to the mechanism to present a very amusing toy.

40 I claim:—

1. A toy comprising a table, a spring board mounted on the table, a train of clock gearing mounted under the table, a tappet actuated by the gearing, a spring connected

to the spring board in the path of said tappet, 45 and an articulated figure mounted above the spring board.

2. A toy comprising a table, a board connected to the table by means of a spring, a train of clock gearing secured underneath the 50 table, a tappet connected to one of the shafts of said gearing, a spring connected to the board and having an arm projecting in the path of said tappet, an articulated figure mounted above the spring board, means for 55 winding said clock mechanism and means for regulating the speed of the same.

3. A toy comprising a table, a spring board connected to said table by a spring, a train of clock gearing suspended from the 60 frame, a tappet for actuating said board, a main shaft carrying a wheel in mesh with a wheel upon a vertical shaft, an umbrella on the upper end of said shaft, an articulated figure mounted above the spring board, a 65 flag staff provided with an arm to engage said main shaft for starting and stopping the gearing and a lever provided with an arm for engaging one of the shafts to regulate the speed.

4. A toy comprising a table, a spring board connected to the table, a tappet, a train of gearing, a spring connected to the spring board and provided with an arm disposed in the path of the tappet, an articulated figure 70 mounted above the spring board and a shaft having a cranked end disposed over the end of the spring board to be operated thereby, means for winding the mechanism, means for 75 starting and stopping the mechanism and means for regulating the speed thereof.

In testimony whereof I affix my signature in presence of two witnesses.

ROBERT E. PETEET.
